CROSS ROLL STRAIGHTENER MACHINE

DESCRIPTION

The present invention relates to load-limiting devices, and particularly to a load-limiting device for a cross roll machine.

Although the invention is particularly applicable to a cross roll machine, and will be described with reference thereto, it will be appreciated that the invention has broader application with other types of machines.

A cross roll machine is well known employed for straightening, polishing or derodding tubular workpieces. The machine consists of a plurality of pairs of rolls, preferably three pairs, aligned along the machine axis with the upper roll of each pair being oriented at one angle with respect to the machine axis and the lower roll at a different angle. The roll surfaces are curved to conform generally with the workpiece surface, and are rotationally driven. The roll pass center of the middle roll pair is slightly offset vertically from the roll pass centers of the receiving and delivering roll pairs so that the workpiece advances forwardly through a bending arc. Rotation of the rolls causes the workpiece also to rotate as it advances, this working of the workpiece over its entire length and through all its axes imparting straightness and eliminating out-of-roundness.

In order to obtain close-tolerance straightness and eliminate all out-of-roundness, it is necessary that the cross roll machine be completely rigid; that is, that the spacing between upper and lower rolls be maintained constant during normal loads. In building a cross roll machine, all of the components of the machine are deliberately designed to avoid elasticity.

In operation, the pass openings between the machine's three sets of rolls are carefully adjusted to exactly suit the outside diameter of the round workpiece being straightened, to permit its easy entry through the roll passes; and at the same time cause the upper and lower rolls to grip the workpiece positively and exert sufficient tractive and rotative contact pressures on the workpiece to advance it longitudinally and spirally through the pass openings.

One practice which frequently is employed is the elimination of unwanted ovality in tubular workpieces by adjusting the upper and lower cross rolls to a roll opening slightly smaller than the outside diameter of the workpiece. This practice may safely be employed with tubular workpieces having thin, normal or even fairly heavy wall thicknesses, since, as long as the tubular workpieces fall within the machine's rated outside diameter size, wall thickness and workpiece material strength limits, they can be deformed by pressure between the opposed cross rolls into a temporary flattened oval shape, from which shape the tubular workpieces emerge with improved roundness.

Even where the roll pass openings are appreciably smaller than the tubular workpiece outside diameters, those workpieces which can readily be ovalled by roll pressure can enter without difficulty between the opposed upper and lower cross rolls, particularly if the cross rolls of the first or receiving pass are adjusted to a slightly open angular position so to present to the oncoming front end of the tubular workpiece a funnel-shaped entrance path.

However, the cross roll machines have heretofore been limited to use with readily deformable workpieces, and generally are not recommended for straightening, polishing or derodding extra heavy-wall tubular workpieces of high-strength material; or solid-bar workpieces. The reason for this is that extreme care must be exercised in accurately adjusting the cross roll openings to suit the workpieces of this category, and if an oversized workpiece or one of extreme unevenness in this category is forced between the cross rolls, the machine being extremely rigid, such workpieces being not readily deformable to an oval shape could upon entering immediately exert between the opposed cross rolls a separating force of sufficient magnitude to strain the roll necks and roll neck bearings to stress levels destructively greater than their ultimate strength capacities.

The problem is particularly serious with respect to the roll neck portions and roll neck bearings of the rolls. The rolls at opposite ends of the roll body are supported by axially extending neck portions, rotating in frame roll neck bearings. To provide adequate clearances in a cross roll machine, particularly between the roll bearing housings and the workpiece, the roll neck bearings must be as close as possible to the roll bodies limiting the permissible radii of the fillets between the roll necks and bodies, creating stress points at these radii.

It is important to note that the problem is acute only with solid-bar or heavy-wall, high-strength, material of slightly oversized diameter. Workpieces having an outside diameter considerably larger than the roll pass openings will refuse to enter the constricted space between the cross rolls, since they are not readily deformable. This refusal to enter occurs even when the cross rolls are angularly adjusted so as to present to the front end of the workpiece a funnel-shaped opening.

It is an object of the present invention to overcome the above limitation of cross roll machines, and in particular to provide a cross roll machine capable of safely straightening, polishing or derodding extra heavy-wall tubular workpieces of high-strength material and solid-bar workpieces, in addition to tubular workpieces capable of being readily deformable to an oval shape.

It is further an object of the present invention to provide a load-limiting device for a cross roll straightener which is simple and inexpensive, and in addition which has the characteristic of functioning as a rigid connection or member under all but an overload condition, providing a short rapid almost instantaneous relief stroke suitable for slightly oversized pieces when an overload condition occurs.

In accordance with the present invention, there is provided a cross roll machine comprising a housing, upper and lower roll carrier means supported in said housing, upper and lower rolls supported by said roll carrier means, one of said roll carrier means and said housing defining vertically spaced-apart cooperating surfaces disposed so at a load tends to move said surfaces together, further including a plurality of dish springs between said surfaces, and means for preloading said dish springs to maintain a substantially constant spacing between said surfaces under normal load conditions.

Preferably, the upper roll carrier means is vertically adjustable relative to the housing and comprises a roll carrier frame which is rotatable about a vertical axis in the housing, including adjusting means for raising and lowering the frame, said adjusting means comprising a vertical downwardly extending threaded shaft and an annular screw box member threaded onto said shaft. The roll carrier frame defines a vertically oriented bore receiving the screw box member and an upwardly facing seat which is spaced from a downwardly facing surface of the screw box member, cooperating therewith to define that space which is compressed in the event of an overload condition.

Preferably, at least two pairs of dish springs are used, the springs in each pair being seated so that the concave surfaces thereof are facing each other, the pairs being in back-to-back relationship.

The invention and advantages thereof will become apparent upon further consideration of the specification, with reference to the accompanying drawings, in which

FIG. 1 is an elevation view of a cross roll machine illustrating the concepts of the invention;

FIG. 2 is an enlarged cross section view taken along line 2-2 of FIG. 1;

FIG. 3 is a partial section view taken along line 3-3 of FIG. 2; and

FIG. 4 is an enlarged partial perspective view of a nest of dish springs in accordance with the invention.

Referring now to the drawings, wherein the showings are for the purpose of illustrating the preferred embodiment of the invention only and not for the purpose of limiting the same, the Figures show a cross roll straightener A which is provided with upper and lower housings B and C respectively. The upper and

75

lower housings support a plurality of opposed upper and lower roll carrier frames D which in turn support roll pairs R1, R2 and R3.

Referring to the drawings in detail, the cross roll straightener, generally indicated by the letter A, comprises a base 12, below the lower housing C, on which there is supported the components of the machine, many of which are conventional and form no part of this invention. The lower housing C is supported directly on the base 12, the upper housing B being held above the lower housing by means of support columns 14 connected to the lower housing. The cross roll straightener defines a substantially horizontal longitudinal axis along which tubes, bars or other workpieces of circular cross section are threaded, the workpieces being engaged in the pass openings between the upper and lower rolls 16 and 18 of the roll pairs R1, R2, and R3, the openings between the rolls being sufficient to accommodate the workpiece but functionally engage its surface. In the example illustrated in FIG. 1, the roll pair R1 represents the receiving roll pair, and the roll pair R3 represents the delivering roll pair. The upper rolls 16 of each of these roll pairs are arranged in the same horizontal plane and the lower rolls 18 of the two roll pairs are arranged in a plane which is substantially parallel to the upper plane; the center roll pair being displaced slightly upwardly with respect to the receiving and delivering roll pair to produce a bending arc through which the rotating axially moving workpieces extend. This rotational and axial movement, through a bending arc, flexes and rounds the workpiece along its entire length and through all of its axes to impart close-tolerance straightness to the workpiece and eliminate out-of-roundness.

Each roll of each roll pair is provided with a concave surface 20 which conform generally with the surface of the workpiece, the upper roll 16 of each pair being angled at one angle with respect to the machine axis, the lower roll 18 of each roll pair being angled at a different angle, so that looking from the top down, the axes of the roll pairs are crossed. The rolls preferably are individually driven by drive means 24 which are not a part of this invention, and rotation of the concave surfaces of the rolls, the latter angled with respect to the direction of travel of the workpiece, causes the desired rotational and axial movement of the latter.

The shape of the rolls is shown in FIGS. 2 and 3 in more detail, each roll comprising a roll body 26 of circular cross section having a generally constricted center section 28 so that the roll surface profile in an elevation view is concave. Extending axially from the roll body at opposite ends thereof are opposed necks 30 and 32 which are of substantially lesser diameter than the roll body 26.

Referring to FIG. 2, the upper rolls 16 are supported so that they can be moved vertically up or down, the lower rolls 18 being fixedly held relative to the lower housing C.

To support the upper rolls, the necks 30 and 32 of the rolls are contained in roll neck bearing housings 34 and 36 which are part of an inverted U-shaped roll carrier frame yoke 38. Annular ball bearings 40 and 42 permit rotation of the roll necks within the roll bearing housings.

The yoke 38 is an integral part of a roll carrier frame 44 which is provided with a cylindrical carrier frame body 46 extending upwardly into a vertically extending cylindrical socket 48 formed within the cross roll machine upper housing B. This socket is sufficiently deep to accommodate substantially all of the carrier frame body 46, and slidably receives the body with a close sliding fit to hold the body against lateral displacement.

The carrier frame body in turn is provided with an axial bore 50 which extends all the way through it and receives a shank 52 of an adjusting mechanism 54. The latter is threaded along its lower end 56 to receive an internally threaded nutlike screw box member 58, rotation of the adjusting mechanism shank 52 relative to the screw box member causing the latter to move upwardly or downwardly on the shank threaded end.

The screw box member 58 is secured with the carrier frame body 46, in an annular cavity 60 in the upper end 62 thereof coaxial with but of larger diameter than the bore 50. The

lower end of the cavity 60 terminates in a seat 64 which is spaced from but opposite to the lower end surface 66 of the screw box member 58, to define an annular space 68. At its upper end, the cavity is bridged over with a washerlike retaining ring 70, bolted to a shoulder portion 72 of the carrier frame body by a plurality of spaced bolts 74, the upper end 75 of the screw box member bearing against the underside of ring 70.

To prevent the screw box member 58 from rotating with rotation of the adjusting mechanism shank 52, a plurality of keys 76 are positioned between the retaining ring 70 and the screw box member 58, seated into both, so that the screw box member does not turn within the carrier frame body 46.

To support the adjusting mechanism in the housing B, the shank 52 of the mechanism is provided with an upper end 78 which penetrates an upper portion of the housing, and a roller thrust bearing 80 around the shank upper end 78 seats between an annular shoulder 82 on the shank and the upper surface 84 of the housing. The roller bearing supports the weight of the roll carrier frame and rolls, and permits the adjusting mechanism to turn within the housing.

Spaced from the roller bearing 80 is a second annular bearing 86 on the shank upper end engaging the underside or upper inner surface 88 of the housing B. When an upward force is exerted against the upper roll, this force is transmitted through the roll carrier frame body 46 onto the screw box member 58 (in a manner to be described), onto the adjusting mechanism shank 52, and through the bearing 86 against the surface 88 of the housing.

To transfer this upward force from the carrier frame body 46 to the screw box member, in accordance with the present invention, a plurality of dish springs 90 are positioned in the annular space 68 between the screw box member and the roll carrier seat 64. These dish springs are illustrated in detail in FIG. 4, and comprise washerlike members having a hollowed (or concave) surface 92 between inner and outer circular edges 94 and 96, and a back (or convex) surface 97. In the present invention, it is contemplated that they be utilized in pairs, with the dished hollowed surfaces facing each other and with the inner and outer edges of each spring member bearing against the corresponding edges of another spring member.

40 In the embodiment illustrated, two pairs of the dish springs are utilized with the back surface 97 of one spring of one pair bearing against the back surface 97 of one spring of the other pair.

45 The dish spring is a well-known type of spring, manufactured under a number of trademarks, one suitable for use in accordance with the present invention being the Belleville (registered trademark) spring.

Each spring nest must act as a solid nondeflecting roll support member under all load conditions anticipated in normal straightening service. This requires that the dish springs be precompressed, and this is accomplished by placing a plurality of shims 98 between the retaining ring 70 and the carrier frame body shoulder 72, the bolts 74 which hold the retaining ring to the carrier frame body penetrating the shims. Depending upon the number of shims used, the carrier frame body 46

60 is lowered a predetermined amount relative to the screw box member 58, the precompression being increased by simply reducing the number of shims forcing the screw box member downwardly in cavity 60 reducing the depth of the annular space 68 between the screw box member and the annular seat 64.

70 In operation, the dish springs are subjected to a predetermined amount of precompression by adjustment of the number of shims used, and after this, the vertical height of the upper roll relative to the lower roll, or the pass opening between the rolls is adjusted simply by rotating the handle 102 of the adjusting mechanism raising or lowering the screw box member member 58 relative to the adjusting mechanism shank 52. This in turn raises or lowers the carrier frame body and roll.

In the event an oversized piece which cannot readily be ovalled is accepted in the roll pass opening between opposed cross rolls, the excess load is transmitted through the roll necks and carrier frame into the dish springs, collapsing the latter in the very short upward stroke which relieves the over-load condition.

The unique suitability of the dish springs in the above application or service is illustrated in the following example which shows the manner in which the given characteristics of the dish springs exactly match requirements.

EXAMPLE

Critical factors are deflection, preload, and maximum load, capabilities of the spring nest.

Experience has shown that nondeformable workpieces having outside diameters measuring more than approximately 107.5 percent of the roll-opening dimension will not enter between the cross rolls. Accordingly, only nondeformable workpieces of outside diameter greater than 100 percent but less than approximately 107.5 percent of the roll-opening dimension are capable of producing destructive overloads.

In the example under consideration, the machine maximum rated nondeformable workpiece outside diameter is 0.750 inch. This means that the spring nest must be capable of relief deflection of at least 0.056 inch (0.750 x 0.075 inch). To provide extra insurance against possible inaccuracies in parts, dimensions or spring characteristics, a larger deflection capability of 0.125 inch is desirable.

The cross roll machine also is provided with a rated maximum force exerted on one bending roll during bend straightening of a steel bar (0.75 inch diameter, minimum yield strength of 70,000 p.s.i.) calculated at 1,440 pounds. This means that the spring nest must be capable of being pre-loaded so that it is completely rigid and acts as a solid non-deflecting roll support member up to 1,440 pounds load. It further means that the spring nest should have at least 0.125 inch deflection capability after being deflected by the 1,440 pounds preload.

The rated maximum force for each neck will be half of 1,440 pounds or 720 pounds.

The maximum design load capacity of a roll, defined as that load which creates a maximum ultimate fiber stress of 45,000 p.s.i. in tension in the radius at the junction between the roll neck and roll body (which 45,000 p.s.i. is in turn one-third of 135,000 p.s.i. maximum yield strength of the roll metal), is calculated at 2,700 pounds or 1,350 pounds on each roll neck at the centerline of each roll neck support bearing.

Calculations show that the above roll load capacity of 2,700 pounds affords a 6 to 1 safety factor over normal loading up to 1,440 pounds, and further is safely within the rated combined dynamic capacity of the rolls antifriction bearings (calculated at 4,730 pounds).

In any event, the spring nest must have a deflection and loading capability such that at maximum (flat) deflection, the load force or nest capacity is equal to or slightly greater than 2,700 pounds.

The following calculations illustrate how the above criteria are met.

The spring selected had the following characteristics: o.d. = 3 1/8 inches, i.d. = 1 9/16 inches, R_1 (radius convex side) = 50 percent of o.d. = 1.5625 inches, R_2 (radius concave side) = 0.95 R_1 = 0.95 x 1.562 inches = 1.483 inches

Number of springs—in series—per nest = 4

Each spring disc: thickness— t = .134"

Each spring disc: maximum deflection— h (free height to flat height) = .0625"

Each spring disc: free height = $t + h$ = .134" = .0625" = .1965"

Overall nest free height = $4 \times (.134" + .0625")$ = .786"

Overall nest flat height = $4 \times .134"$ = .536"

Overall nest total deflection = $4 \cdot h = 4 \times .0625"$ = .250"

The flat maximum capacity P_2 , or that force required to flatten the nest, is calculated to be 3,262 pounds. This is calculated using the formula

$$P_2 = \frac{Eht^3}{.91MR^2}$$

Wherein

$$E = \text{modulus of elasticity} = 30,000,000;$$

$$M = \text{o.d./i.d. ratio factor} = 0.689$$

$$0.91 = \text{constant from Poisson's ratio for steel.}$$

This capacity is 21 percent higher than the 2,700 pounds maximum load capacity of the rolls, so that even at maximum load capacity of the rolls, there clearly is available additional capacity in the nest.

15 In terms of reserve deflection, this works out as follows:

$$\text{Spring rate of nest} = \frac{P^2}{4h} = \frac{3262}{.250} = 13,048 \text{ lbs. per 1"}$$

20 For preload of 1440 lbs., nest deflection $f = \frac{1440}{13,048} = .110"$

$$\text{Preload nest height} = .786" - .110" = .676"$$

$$\text{Reserve nest deflection} = 4h - f = .250" - .110" = .140"$$

25 The reserve nest deflection of 0.140 inch after preload deflection is 12 percent greater than the desired minimum amount of working deflection of 0.124 inch, and therefore is clearly satisfactory.

30 In that the maximum flat capacity value of P_2 (3,262 pounds) is only slightly greater than the load capacity of the roll (2,700 pounds), it is apparent that the maximum relief deflection likely to occur (0.056 inch) caused by a 1.075 percent oversized workpiece, will occur at a spring load value, calculated to be 2,166 pounds, well below the 2,700 pounds; roll capacity but of course, well above the 1,440 pounds preload.

35 Advantages of the invention should be apparent. Dimensionwise, the nest of springs is conveniently assembled into the adjusting mechanism for the upper roll. The device acts as a solid nondeflecting roll support member under all load conditions which might be anticipated in normal straightening service, and at the same time, the nest provides the unique short relief stroke required for cross roll, solid-bar or heavy-wall tube straightening. It will be recalled that no relief stroke is required for workpieces so large that the openings between the cross rolls refuse to accept them. Finally the small-dimensioned springs have more than adequate relief load capacity.

40 Although the invention has been described with reference to specific embodiments, variations within the scope of the following claims will be apparent to those skilled in art.

50 What I claim is:

1. In a roll machine including a housing, a roll carrier frame supported within said housing, and a roll supported by said roll carrier frame, the improvement comprising

55 adjusting means for vertically adjusting said roll carrier frame;

56 said roll carrier frame and adjusting means presenting vertically spaced-apart cooperating surfaces, and means structurally associated with said surfaces so that the imposition of a load on said roll tends to move said surfaces together; and

60 a plurality of dish spring means between said surfaces having a stiffness sufficient to maintain the spacing rigidly between said surfaces under normal load conditions and to yield under overload conditions.

65 2. A cross roll straightener machine including a machine axis along which cylindrical stock is threaded;

70 a plurality of opposed upper and lower rolls of roll pairs arranged longitudinally along said axis, the upper rolls being differently angled with respect to the machine axis than the lower rolls;

75 said machine comprising upper and lower housings for said upper and lower rolls;

a plurality of roll carrier frames supported in said upper housing supporting said upper rolls;

adjusting means for vertically adjusting said roll carrier frames;

said roll carrier frames and adjusting means presenting vertically spaced-apart cooperating surfaces, and means structurally associated with said surfaces so that the imposition of a load on said upper rolls tends to move said surfaces together;

a plurality of assemblies of dish spring means between said surfaces, each assembly having a stiffness sufficient to maintain the spacing rigidly between the surfaces under normal load conditions and to yield under overload conditions.

3. A cross roll straightener machine including a machine axis along which cylindrical stock is threaded;

a plurality of opposed upper and lower rolls of roll pairs arranged longitudinally along said axis, the upper rolls being differently angled with respect to the machine axis than the lower rolls;

said machine comprising upper and lower housings for said upper and lower rolls;

a plurality of roll carrier frames supported in said upper housing supporting said upper rolls;

adjusting means for vertically adjusting said roll carrier frames, said adjusting means comprising a vertically extending threaded shank;

a nutlike screw box member threaded onto said shank; each of said roll carrier frames comprising a cavity to receive said screw box member;

said screw box member defining a lower surface and said cavity defining an upwardly facing seat surface spaced from said lower surface;

said roll carrier frames and adjusting means presenting vertically spaced-apart cooperating surfaces, and means structurally associated with said surfaces so that the imposition of a load on said upper rolls tends to move said surfaces together; and

a plurality of assemblies of dish spring means between said surfaces, each assembly having a stiffness sufficient to maintain the spacing rigidly between the surfaces under normal load conditions and to yield under overload conditions, and

said dish springs being disposed between said roll carrier seat and said screw box member lower surface, and encompassing said adjusting means shank.

4. The machine according to claim 3 wherein said roll carrier frame further comprises a retaining ring connected to said roll carrier frame to bridge said cavity above the screw box member whereby said member bears against said retaining

means between said roll carrier frame and said retaining ring to effect a predetermined amount of precompression of the dish springs on tightening the retaining ring to the roll carrier frame.

5. The machine of claim 4 wherein said roll carrier frame defines an upwardly facing shoulder further including bolt means fastening the retaining ring to said shoulder, said means to effect a predetermined amount of precompression comprising a plurality of shims between the shoulder and retaining ring.

6. The machine of claim 4 further including means to prevent the rotation of said screw box member relative to the roll carrier frame.

7. The machine of claim 2 wherein said stand of rolls includes three roll pairs spaced on close centers for precision straightening,

said roll carrier frames each comprising a yoke, said rolls comprising a body and oppositely extending neck portions seated in said carrier frame yokes, the neck portions being of small diameter to permit clearance between said yokes and a workpiece, and limiting the radius of the fillets between the neck portions and roll body to a comparatively small dimension.

25 8. The machine of claim 2 wherein said dish springs are annular washerlike members comprising inner and outer circular edges including oppositely facing hollowed and back surfaces between said edges, said members being arranged in pairs with the hollowed surface of one member facing the hollowed surface of another member, and the outer edges of said members being in contact.

9. The machine of claim 8 including two pairs of dish springs, the back surface of one member of one pair bearing against the back surface of one member of the other pair.

10. A cross roll machine comprising a housing; upper and lower roll carrier means supported in said housing;

upper and lower rolls supported by said roll carrier means; one of said roll carrier means and said housing defining vertically spaced-apart cooperating surfaces disposed so that a load imposed on a roll tends to move said surfaces together;

a plurality of dish springs between said surfaces; and means for preloading said dish springs to maintain a substantially constant spacing between said surfaces under normal load conditions and to collapse said surfaces towards each other under overload conditions.
